Primary Examiner — Ricky Pham(74) *Attorney, Agent, or Firm* — Posz Law Group, PLC(57) **CLAIM**

The ornamental design for a side panel for furniture drawer, as shown and described.

DESCRIPTION

FIG. 1 is a front perspective view of a first embodiment of a side panel for furniture drawer showing my new design;

FIG. 2 is a front view thereof;

FIG. 3 is a rear view thereof;

FIG. 4 is a left view thereof, the right view being a mirror image thereof;

FIG. 5 is a top view thereof;

FIG. 6 is a bottom view thereof; and

FIG. 7 is a rear perspective view thereof.

FIG. 8 is a perspective view of top, front, and left side of a second embodiment of the side panel for furniture drawer showing my new design;

FIG. 9 is a front view thereof;

FIG. 10 is a rear view thereof;

FIG. 11 is a left view thereof, the right view being a mirror image thereof;

FIG. 12 is a top view thereof;
FIG. 13 is a bottom view thereof; and
FIG. 14 is a rear perspective view thereof.
FIG. 15 is a perspective view of top, front, and left side of a third embodiment of the side panel for furniture drawer showing my new design;
FIG. 16 is a front view thereof;
FIG. 17 is a rear view thereof;
FIG. 18 is a left view thereof, the right view being a mirror image thereof;
FIG. 19 is a top view thereof;
FIG. 20 is a bottom view thereof; and
FIG. 21 is a rear perspective view thereof.
FIG. 22 is a perspective view of top, front, and left side of a fourth embodiment of the side panel for furniture drawer showing my new design;
FIG. 23 is a front view thereof;

FIG. 24 is a rear view thereof;
FIG. 25 is a left view thereof, the right view being a minor image thereof;
FIG. 26 is a top view thereof;
FIG. 27 is a bottom view thereof; and
FIG. 28 is a rear perspective view thereof.
FIG. 29 is a perspective view of top, front, and left side of a sixth embodiment of the side panel for furniture drawer showing my new design;
FIG. 30 is a front view thereof;
FIG. 31 is a rear view thereof;
FIG. 32 is a left view thereof, the right view being a mirror image thereof;
FIG. 33 is a top view thereof;
FIG. 34 is a bottom view thereof; and,
FIG. 35 is a rear perspective view thereof.
